UNITED STATES PATENT OFFICE

122,179

DESIGN FOR A TOBACCO POUCH

Richard B. Brinnon and Max D. Brinnon,
Wichita, Kans.

Application March 28, 1939, Serial No. 83,881

Term of patent 3½ years

To all whom it may concern:

Be it known that we, Richard B. Brinnon and Max D. Brinnon, citizens of the United States of America, residing at Wichita, in the county of Sedgwick and State of Kansas, have invented a new, original, and ornamental Design for a Tobacco Pouch, of which the following is a specification, reference being had to the accompanying drawing, forming part thereof.

The figure is a perspective view of the tobacco pouch, showing our new design. The side of the pouch opposite to that shown in the figure is plain.

We claim:

The ornamental design for a tobacco pouch, as shown and described.

RICHARD B. BRINNON.
MAX D. BRINNON.
